UNITED STATES PATENT OFFICE

2,133,118

FLUID CONTROL MECHANISM

Carl F. Sibbe, Philadelphia, Pa., assignor to
American Engineering Company, Philadelphia,
Pa., a corporation of Pennsylvania

Application September 27, 1935, Serial No. 42,495

11 Claims. (Cl. 103—38)

This invention relates to fluid systems, and more particularly to the control mechanisms employed in such systems.

One object of the present invention is to generally improve certain hydraulic control mechanisms of the general type disclosed in United States patent to Earl Cannon No. 1,656,034, and to adapt such devices for use in connection with hydraulic presses and similar apparatus.

Another object is to provide certain improved features to control mechanisms of the above type, which permits operation thereof through a predetermined cycle.

Another object is to provide an improved control for pumps which functions to first place the pump on working stroke, so that a platen or other apparatus operated thereby will move toward the work, to then reverse the discharge of the pump after a predetermined pressure has been exerted upon the work to cause the platen to move away from said work, and when the platen has reached its upper limit of travel, to cause the pump to be returned to the neutral position and be retained in this position until a new cycle of operation is desired.

A further object is to provide adjustable stop means on the hydraulic press associated with the control mechanism to limit the travel thereof in one direction.

A further object is to provide novel by-pass means between the pump and the press so constructed as to stop the movement of the platen toward the work at any position between its limits of travel.

A further object is to provide improved mechanical and electrical control devices for stopping the movement of the platen, and for conditioning the control apparatus for a new cycle of operation.

Other and further objects will become apparent as the description of the invention progresses.

Of the drawings:

Fig. 1 is a diagrammatic view, partly in section showing my improved control mechanism associated with a hydraulic press.

Fig. 2 is a plan view of the pump and associated control mechanism.

Fig. 3 is an enlarged detail sectional view taken substantially along line 3—3 of Fig. 2.

Fig. 4 is an end view of the mechanism shown in Fig. 3 with certain of the actuating rods removed, looking from right to left thereof.

Fig. 5 is a plan view partly in section of the timer mechanism associated with the pump control.

Fig. 6 is an end view of the mechanism shown in Fig. 5, showing particularly the indicating mechanism associated therewith.

Fig. 7 is a sectional view taken substantially along line 7—7 of Fig. 5, showing the stop nuts 5 of the timer mechanism separated.

Fig. 8 is a sectional view taken substantially along line 8—8 of Fig. 3.

Fig. 9 is a sectional view taken substantially along line 9—9 of Fig. 3, showing the position of 10 the parts when the toggle passes through its mid-position.

Fig. 10 is a view similar to Fig. 9, but showing the position of the parts when the toggle has been operated to one of its limiting positions.

Fig. 11 is a similar view showing the position of the parts when the toggle has been actuated to another of its limiting positions of adjustment.

Fig. 12 is a diagrammatic detail view showing different positions of the upper end of the toggle 20 and the latch mechanism therefor when the upper arm of the toggle moves in the direction indicated by the arrows.

Fig. 13 is a similar view showing various positions assumed by the upper end of the toggle and 25 the latch therefor when the latter swings in the opposite direction indicated by the arrow.

Fig. 14 is an end view partly in section taken substantially along line 14—14 of Fig. 12.

Fig. 15 is a diagrammatic view of an alternative 30 construction showing electric operating and control means for certain of the elements thereof, and

Fig. 16 is an enlarged detail view partly in section of certain by-pass valves and the operating means therefor.

Referring to the drawings, the numeral 1 indicates a fluid system comprising in the present instance a variable stroke reversible discharge pump P, and an hydraulic press H. Pump P may be mounted in any suitable manner upon a bed plate 2, having provided therein a fluid reservoir 3, and in the present instance is driven by an electric motor 4, also suitably mounted upon said bed plate. Pump P may be connected to the upper end of a fluid motor A of the press by means of a pipe 6 and to the lower ends of fluid motors B and B' of said press by a pipe 7 and branch pipes 7' and 7'', respectively. Pump P may be of the general type shown and described in United States Patent No. 1,077,979, which includes a stroke control element 8 (Figs. 3 and 5) whereby the quantity and direction of flow of fluid through the pipes 6 and 7 may be varied, the construction being such that when the shiftable element 8 is in the position shown in Fig. 4 55

fluid is delivered under pressure through the pipe 6 and is drawn into the pump through pipe 7, but when the control element 8 is in the opposite position shown in Fig. 10, fluid is delivered 5 through the pipe 7 and drawn in through the pipe 6. However, when shiftable element 8 is in its intermediate or neutral position there is no flow through either of the pipes 6 or 7. The stroke 10 of the shiftable element 8 may be controlled by the timer mechanism 9, shown more particularly 15 in Figs. 5 and 7. This mechanism comprises a pair of spaced rods 11 which are secured at their inner ends to the control element 8. The outer ends of these rods rigidly support a crosshead 12 which may be actuated in opposite directions between a pair of spaced stop nuts 13 and 14. These nuts are respectively mounted on oppositely threaded sections 15 and 16 of a shaft 17 which is journaled in a bearing 18 supported by a bracket 20 secured in any suitable manner to the pump casing. When the shaft 17 is turned in one direction, the stop nuts 13 and 14 separate to increase the space between, and consequently the movement of the crosshead 12 and the control 25 element 8. However, when the shaft 17 is turned in the opposite direction the stop nuts 13 and 14 are moved toward each other to decrease the movement of the crosshead 12. When the nuts 13 and 14 finally clamp the crosshead to prevent 30 a further movement thereof, the control element 8 is in the mid or neutral position. Should it be desirable to permit the control element 8 to move in one direction a greater amount than in the other it is only necessary to vary the 35 relative spacing of the stop nuts 13 and 14 with respect to the crosshead 12. Such a change thus permits the pump to deliver a greater volume of fluid to one side of the system than the other, and also affords an accurate neutral setting. 40 The stop nuts 13 and 14 are prevented from turning when the shaft 17 is actuated, as above described, by means of a guiding rib 21 which extends from an arm 22 of the bracket 19 into a recess 23 of the stop nuts 13 and 14. Arm 22 has 45 one end secured to the pump and the other end to an outer hub portion 24 which is provided with an internally threaded aperture 25 adapted to receive the correspondingly threaded bearing 18. The bearing 18 is thus adjustably mounted. 50 The shaft 17 may be locked against axial movement by means of a pair of collars 26 operatively associated with opposite ends of the bearing 18. The supporting bracket 19 is provided with an additional arm 27 which extends from the hub portion 24 to the pump. A hand wheel 28 55 may be mounted on the outer end of operating shaft 17 to effect operation thereof.

Since it is desirable to know at all times the speed of the motors A and B, B' of the hydraulic 60 press H, an indicator 29 is provided. This indicator comprises a gear wheel 31 having a rotatable mounting on a stud 32 supported by the bracket arm 27. A pointer 33 is rigidly secured to the stud 32 adjacent one face of gear wheel 65 31. The latter may be actuated in accordance with a movement of the stop nuts 13 and 14, and hence variations in the stroke of the pump P by means of a pinion 34, which is so mounted on the shaft 17 as to mesh with the gear wheel 70 31. The indicator 29 may be calibrated so as to have a zero setting when the control element 8 and the associated parts are in the mid or neutral position.

Mechanism 35 is also provided whereby the 75 stroke controlling element 8 may be oppositely

actuated from one extreme position through neutral to the other extreme position only when the pressure in the system exceeds a predetermined value. The mechanism 35 is also adapted to counteract the tendency of the stroke controlling element 8 to return from advance position to the neutral or mid position. The mechanism 35 for accomplishing these results comprises a toggle 36 having an upper arm 37 and a lower arm 38, as shown more particularly in Figs. 1 and 3. The lower arm 38 comprises a tubular section 39, a lower end 40 of which is closed and provided with trunnions 41 which are journaled in spaced bearings 42. An upper open end 43 of the tubular section 39 may be closed by a telescoping cap section 44 having trunnions 45 which are journaled in the lower ends 46 of a pair of strap members 47, constituting the upper toggle arm 37. The strap members 47 may be pivotally mounted on a pin 48 which is supported on a section 49 of a bracket 51 secured to the casing of pump P. The portion of the bracket 51 immediately above section 49 is recessed to provide spaced abutments 52 and 53 for a member 54, having trunnions 55 journaled in the adjacent ends of the strap member 47. The spacing of the abutments 52 and 53 corresponds to the maximum movement of the control element 8, which in turn is controlled by the maximum operation of the stop nuts 13 and 14. The member 54 may be resiliently held in engagement with one or the other of the abutments 52 and 53 by means of a spring 56, one end of which abuts against the telescoping casing 44 and the other against the adjustable seat 57 mounted on a threaded screw 58 extending through the lower end 40 of the tubular section 39. Thus the member 54 may be actuated from engagement with one of the abutments, say 53, into engagement with the other abutment 52, only when the line of action of the spring 56 is sufficiently shifted beyond the dead center line of the toggle.

The toggle, or so called load and fire mechanism 36, may be actuated as just described, by means of a pair of fluid motors 59 and 61, which are respectively connected to the opposite sides of the fluid power system represented by the pipes 6 and 7, the pump P and the motors A and B, B' of the hydraulic press. These motors comprise cylinders 62 and 63 constituting portions of the bracket 51, and a pair of inter-connected plungers 64 and 65, respectively. A member 66 is rigidly secured to a central portion of the plungers 64 and 65 and is provided with trunnions 67 which are journaled in the strap sections 46 that constitute the upper toggle arm 37. Leakage around plungers 64 and 65 may be prevented by packing 68 and a pair of glands 69 and 71, which are respectively clamped to the cylinders 62 and 63 by a pair of tie rods 72 and nuts 73, as shown particularly in Figs. 1 and 4.

Since the movement of the member 54 between the abutments 52 and 53 corresponds to the maximum movement of the stroke controlling element 8, I provide mechanism 74, Figs. 3, 4, 9, 10 and 11, inclusive, which permits variations in the movement of the element 8 by the timer 9 independently of the spring-loaded toggle mechanism 36. The mechanism 74 comprises a rod 75 which supports the member 54 and extends through aligned apertures in the abutments 52 and 53. These apertures are sufficiently large to receive a pair of sleeves 76 and 77, respectively. The sleeves respectively abut against opposite sides of the member 54 and nuts 78 on the ends of the rod 75.

75. Hence when the member 54 is actuated by the toggle mechanism 36, the rod 75 and the sleeves 76 and 77 are correspondingly moved.

5 A pair of crossheads 79 and 81 are apertured to receive slidably the sleeves 76 and 77, respectively, and may be forced into engagement with the nuts 78 on the ends of the rod 75 by means of a pair of springs 82 and 83. The springs 82 and 83 encircle rods 84 and 85 which extend from a pair 10 of guide rods 86 and 87 slidably mounted in the pump P, respectively. The guide rods 86 and 87 are connected to the stroke-controlling element 8. The rods 84 and 85 pass through apertures in the opposite ends of the inner crosshead 81 and are 15 provided with shoulders 88 and 89 against which said crosshead may be actuated by the force of the springs 83 and 82. The outer crosshead 79 is similarly apertured to receive the ends of the rods 84 and 85 which respectively terminate in 20 shoulders 91 and 92 formed by adjusting nuts 93 and 94.

Considering the operation of the toggle mechanism 36, when the member 54 is moved from the intermediate position shown in Fig. 9 to that in 25 Fig. 11 under the action of said toggle mechanism, the mechanism 74 is moved bodily until the crosshead 12 engages the stop nut 14 of the timer mechanism 9. Should the stop nut 14 be so positioned that the crosshead 12 engages the same before the toggle-operated member 54 engages the abutment 53, the movement of said member 54 is not interfered with, inasmuch as the springs 82 and 83 collapse to permit the continued movement 30 of the inner crosshead 81 and the rod 75. The final position of these parts is illustrated in Fig. 35 11. The force of the springs 82 and 83 is such that they not only counteract the normal tendency of the control element 8 to move to its mid-position, but also prevent a relative movement between the crosshead 79 and the spring supporting 40 rods 84 and 85, until the control element 8 has moved the desired extent as defined by the position of the stop nut 14.

When the toggle mechanism 36 is actuated from the advanced position above described, through 45 the neutral position of Fig. 9, the line of action of the spring 56 is changed, so that the member 54 is snapped into engagement with the opposite abutment 52. The position of the parts 50 is now as shown in Fig. 10. Here again the nut 13 is so positioned by the timer mechanism 9 that the control element 8 cannot be moved the maximum distance from its mid-position, as defined 55 by the space between the abutment 52 and the adjacent side of the member 54 when the latter is in the position shown in Fig. 9. The line of action of the spring 56 being now in the opposite direction, the member 54 is positively held in engagement with the abutment 52 until a further 60 operation of the toggle mechanism 36. The pump P is thus reversed for each movement of the toggle mechanism 36.

Considering the operation of the control mechanism thus far described, it is seen that when the driving motor 4 is energized, and the shiftable control element 8 is maintained in its neutral position by the timer mechanism 9, the pump P fails to discharge through either of the pipes 6 and 7. However, when this timer mechanism 9 is operated to separate the stop nuts 13 and 14 the shiftable element 8 is actuated under the force of the springs 82 and 83 until the crosshead 12 engages one or the other of the stop nuts 13, 14, depending upon which abutment the toggle actuated member 54 it is in engagement with. Assuming

the parts to be in the position shown in Fig. 11, fluid is discharged through the pipe 6 to the fluid motor A. When the motor A has actuated the platen associated therewith, hereinafter described, into engagement with the work, the pressure in the pipe 6, and consequently the fluid motor 61, builds up to a value sufficient to cause the latter to actuate the toggle arm 37 against the force of the spring 56 until the line of action of the latter changes, whereupon the toggle mechanism 36, and the control element 8 are snapped into the position shown in Fig. 10. Thus the stroke control element 8 is positively actuated from its advance position in one direction to its 10 advance position in the other direction, and the platen correspondingly reversed only when the pressure in the fluid system reaches the predetermined value at which reversal is to occur. Moreover, pump P is held on stroke independent of its tendency to return to its no-stroke or mid-position. Should it be found desirable to cause the pressure in one side of the system, say in the pipe 6, to reach a higher value than that on the other side of the system before the pump P is reversed, the plunger 65 may be made smaller 15 than the plunger 64, as shown in Fig. 3. The control mechanism thus far described is fully disclosed in the patent to Earl Cannon, hereinbefore referred to.

The present invention contemplates certain improvements and additions to this mechanism, as well as to the hydraulic press H, and to the control circuits between the pump and the press, which will now be described in detail.

Referring more particularly to Figs. 1 to 4, it 30 will be seen that the upper ends of levers 37 of the toggle mechanism 36 extend above bracket 51, and have provided therein a pin 100. Pin 100 is adapted to engage the lower surface of a pair of spaced levers 101 pivotally supported at one end 35 thereof, as shown at 102, to an extension 103 of bracket 51. Levers 101 are integrally connected by spaced cross members 104 and 105, respectively. Extension 103 is provided with a horizontal projection 106 overlying the pivoted end 40 of levers 101. A set screw 107 is mounted near the outer end of projection 106 which engages an adjustable spring seat 108, and a spring 109 extends between said spring seat and the cross member 105. Thus, when spring 109 is placed 45 under compression it urges levers 101 downwardly against pin 100. Levers 101 are provided with a pair of transversely aligned notches 110, which receive pin 100 when the toggle 36 is in its neutral or vertically aligned position, as shown in full 50 lines in Fig. 3.

Pivotedly supported on pins 111 and extending inwardly from the inner sides of levers 101, is a depending plate 112 having extensions 113 provided at the opposite ends thereof. When the 55 upper end of the toggle moves in the direction of the arrows shown in Fig. 13, pin 100 will engage plate 112 and cause the extensions 113 thereon to close the open end of notches 110 and thereby permit the toggle mechanism to complete its 60 movement in the reverse direction, as hereinbefore described. As pin 100 clears plate 112 the latter will move to its normal vertical position by gravity. If desired, a spring may be employed to assure the return of said plate to normal position 65 when released by pin 100.

Bracket 51 has pivotally mounted at 114 near the upper right hand end thereof (Fig. 3) a cam 115 which is adapted to engage the under side of cross member 104, and thereby swing levers 101 70

upwardly to release pin 100 from notches 110. Also pivotally mounted at 116 to bracket 51 and disposed beneath cam 115, is a lever 117 which is adapted to engage an ear 47' (Fig. 4), extending laterally from one of the strap members 47, to urge the lower end of the toggle to the left (Fig. 3) simultaneously with the operation of the latch levers 101 by cam 115. Integral with cam 115 and lever 117 are actuating arms 118 and 119 respectively, which are pivotally connected at the free ends thereof to a vertically disposed link 120. The lower end of link 120 is pivoted to one end of a lever 121 pivotally mounted intermediate its ends at 122 to a supporting bracket 123. The other end of lever 121 has pivotally connected thereto the upper end of a link 124 to the lower end of which is pivotally connected the free end of an arm 125, also pivotally supported on bracket 123. Arm 125 has integral therewith a laterally extending foot treadle 126 disposed adjacent the hydraulic press H. A spring 127 is secured to and extends between foot treadle 126 and the laterally extending projection 128 of bracket 123. Thus, upon the release of treadle 126 after a depression thereof, spring 127 will restore the latter, as well as cam 115 and lever 117, to normal position.

It therefore is clear that in order to condition the apparatus for a cycle of operation it is only necessary for the operator to depress foot treadle 126, thereby causing the toggle 36 to be operated by its spring 56 to the position shown in Fig. 11 and the right hand position indicated by the broken lines in Fig. 13. The pump will then deliver fluid pressure to motor A, causing the platen connected thereto to descend toward the work. When the platen reaches the work a pressure is developed in the system which is transmitted to the toggle by means of motor 61. When this pressure is sufficient to overcome the pressure exerted by spring 56, the toggle will actuate the pump control 8 in the reverse direction as hereinbefore described, causing the pump to deliver fluid pressure to motors B and B', which return the platen to normal position. As the pin 100 moves toward a central position it will engage plate 112 causing the extensions 113 thereon to close the open end of notches 110, thereby permitting pin 100 to move to the extreme left hand position shown in broken lines in Figs. 12 and 13. When the platen reaches its upper limit of travel, pressure again will build up in the system, causing motor 59 to swing the toggle toward neutral position, and when pin 100 registers with notches 110, spring 109 will urge levers 101 downwardly to lock the toggle in this position. The apparatus is now conditioned for a new cycle of operation.

In the event it is desired to have the platen reciprocate without coming to rest at the end of each cycle of operation a spring-urged latch 130 is provided. Thus when the treadle is moved downwardly to its fullest extent of movement latch 130 will engage the end thereof to hold the parts in operated position. Cam 115 will therefore hold levers 101 out of engagement with pin 100. When moved to operated position the lower end of lever 117 will have cleared the upper end of ear 47' so as not to interfere with the operation of the toggle. The device will now continue to reverse in the manner set forth in the patent to Earl Cannon, previously referred to.

The hydraulic press H comprises a supporting standard 131 having a material-supporting table 132 mounted at the upper end thereof. The upper stationary member 133 of the press H upon

which motor A is mounted, is supported in spaced relation with table 132, by means of rods 134 provided at the corners thereof. These rods are each provided with shoulders 135 and 136 near the upper and lower ends thereof, which respectively engage the under side of member 133 and the top surface of table 132. The reduced portions 137 and 138, respectively, of these rods extend through member 133 and table 132, and nuts 139 rigidly secure the parts in position. The upper surface of the press platen 140 is engaged by the piston rod 141 of fluid motor A, while the lower surface thereof is in engagement with the piston rods 142 and 143 of motors B and B'. Platen 140 is guided in its vertical movement by the rods 134. Motor A is secured in any suitable manner to member 133, while motors B and B' are secured to the under side of table 132, as shown in Fig. 1. Thus, when motor A is subjected to fluid pressure platen 140 will be moved downwardly toward the work, and when a reversal of the fluid in the system is effected, as previously described, motors B and B' operate to return the platen to normal position.

In order to adapt the press for operation upon materials of different sizes, or to enable maximum speed of operation of the press, the travel of the platen must be subject to control. To this end a pair of simultaneously operable, adjustable stops 144 and 145 is provided. These stops are secured to the lower ends of a pair of screw shafts 146 and 147, which extend upwardly through apertures 148 and 149 provided in member 133. Shafts 146 and 147 are actuated by a pair of interconnected, internally threaded bevel gears 150 and 151, supported upon the upper surface of member 133 and held against vertical displacement by guide brackets 152 and 153, respectively, secured to said member 133. Bevel gears 150 and 151 mesh respectively, with a pair of vertically disposed bevel gears 154 and 155, secured to the opposite ends of a shaft 156 mounted for rotation in bearing brackets 157, 157, secured to and extending upwardly from member 133. A handle wheel 158 secured to shaft 156 and disposed between bearing brackets 157 may be employed to rotate bevel gears 154 and 155 which through bevel gears 150 and 151 effect a simultaneous vertical displacement of shafts 146 and 147, and consequently of stops 144 and 145. Thus, when platen 140 engages these stops the pressure in the system will build up, causing motor 59 to actuate the toggle to a neutral position where it will be held in place by the latch levers 101 as previously described. In certain types of work, such, for example, as die setting, it is desirable to have the platen move toward the work as slowly as possible, so that before effecting an operation thereon proper adjustment of all of the parts is assured. To this end a pair of by-pass valves 160 and 161 is provided in pipes 6 and 7 respectively. The upper and lower ports 162 and 163 of valves 160 and 161, respectively, are connected by means of a by-pass pipe 164. As shown more particularly in Fig. 1, valve 160 is provided with an inlet port 166 and an outlet port 167. Valve 160 has also provided therein a pair of interconnected valve elements 168 and 169, which are adapted to engage valve seats 170 and 171 respectively. Fig. 1 shows the parts in normal position wherein valve element 168 is in seated position, thereby preventing the passage of fluid from pipe 6 to pipe 7, while valve 169 is unseated to permit fluid to pass therethrough to motor A, or from motor A back to 75

pump P, depending upon the adjustment of the latter.

Valve 161 is of similar construction, and also has provided therein a pair of interconnected valve elements 172 and 173 which are adapted respectively, to engage valve seats 174 and 175. When the apparatus is in normal position valve element 172 is in seated position and thus prevents the passage of fluid from pipe 7 to pipe 6, while valve 173 is unseated so that fluid passing through pipe 7 will either flow toward or from motors B and B', through its ports 176 and 177, depending upon the adjustment of pump P.

The valve stems 178 and 179 of valves 160 and 161 extend through suitable packing provided in the casings thereof. The lower end of valve stem 178 has secured thereto a laterally extending pin 180 which engages into a longitudinally extending slot 181 provided at the right hand end 20 of a lever 182 pivoted intermediate its ends on an arm 183 of a bracket 184, secured to pipe 6. The left hand end of lever 182 is provided with a laterally extending pin 185 which engages into a slot 186 provided at the right hand end of a 25 second lever 187. Lever 187 is also pivoted intermediate its ends at 188 to another arm 189 of bracket 184.

The upper end of valve stem 179 has also secured thereto a laterally extending pin 190 which 30 engages into a longitudinally extending slot 191 provided at the right hand end of a lever 192 pivotally mounted on the upper end of a bracket 193 secured to pipe 7. These levers are connected for simultaneous operation by means of a 35 lever 194 pivoted intermediate its ends at 195 to the lower end of bracket 193 and a pair of links 196 and 197, as shown in Fig. 1. The extreme left hand end of lever 187 has secured thereto a chain or other mechanism 198, which, as shown 40 in Fig. 1, may be positioned adjacent the hydraulic press H. It therefore is seen that when it is desired to hold platen 140 in any position of adjustment during the downward travel thereof, it is only necessary to pull downwardly on 45 chain 198. This motion is transmitted to the valves through the link and lever mechanism just described, causing seating of valve elements 169 and 173, and unseating of valve elements 170 and 172. When this occurs, fluid passing 50 through pipe 6 will by-pass through valve 160, by-pass pipe 164, valve 161, pipe 7, and thence to pump P. It also is clear that the fluid in motors A, B and B', and the fluid in the portions of pipes 6 and 7 disposed to the right (Fig. 1) of valves 55 160 and 161, will be trapped, thereby forming a hydraulic lock which holds platen 140 against further downward movement. Upon release of chain 193 a spring 199 connected at one end to the left hand end of lever 182 and at the other 60 end to the lower, laterally projecting portion of arm 183 will restore the parts to normal position, and fluid will again flow to motor A and be evacuated from motors B and B' by the action of pump P. By simply manipulating valves 160 and 161 in this manner any desired degrees of adjustment of platen 140 may be effected.

It sometimes is desirable to effect operation of the pump controls and by-pass valves by electrical means. To this end the following mechanism has been provided.

Referring more particularly to Fig. 15, it is seen that the lower end of link 120' passes through a solenoid 200 supported in any suitable manner upon the bracket 123'. A wire 201 connects the upper end of solenoid 200 to a switch

202, secured to table 132' of press H, or at any other suitable location. A second wire 203 connects the lower end of said solenoid to one of the bus bars 204 constituting a source of electric supply, while a third wire 205 connects the other of 5 said bus bars 206 to switch 202. Thus upon depression of switch 202 solenoid 200 will urge link 120' downwardly, causing cam 115' to lift latch levers 111' out of engagement with pin 100'. At the same time lever 117' will actuate the toggle 10 20 36' which in turn operates the stroke adjusting means of pump P, causing the latter to deliver fluid pressure to pipe 6' and suction to pipe 7', as previously described. If it is desired to effect repeated reversals of platen 140' the switch 202 15 is maintained in closed position. Solenoid 200 will then hold cam 115' and lever 117' in operated position. Upon deenergization of solenoid 200 by opening switch 202 a spring 207 disposed between the top of said solenoid, and an abutment 208 at the lower end of link 120' will restore the parts to operative position, and the pump P will consequently be held on neutral when the platen assumes a normal position.

Referring to Figs. 15 and 16, electric means has 25 also been provided to actuate the by-pass valves 160' and 161', mounted respectively in pipes 6' and 7' to control the movement of platen 140'. The construction of these valves is similar to that 30 of valves 160 and 161 shown in Fig. 1, and accordingly, a detailed description thereof is unnecessary. Valve 160' has provided therein a pair 35 of interconnected valve elements 168' and 169', adapted respectively to seat upon valve seats 170' and 171'. Valve 161' has also provided therein a pair 40 of interconnected valve elements 172' and 173' adapted to seat upon valve seats 174' and 175'. When the parts are in normal position, as shown in Fig. 16, fluid is prevented from flowing through the by-pass pipe 164'.

The valve stems 178' and 179' have respectively 45 secured to the free ends thereof, extensions 210 and 211, which form the cores of solenoids 212 and 213. These solenoids are mounted on brackets 214 and 215, secured respectively to pipes 6' 45 and 7'.

Valve element 168' is normally held upon its seat 170' by a spring 216 extending between solenoid 212 and a shoulder 217 provided near the top of extension 210. Valve element 172' is likewise 50 normally held upon its seat 174' by a spring 218 extending between solenoid 213 and a shoulder 219 provided at the lower end of extension 211. A switch 220 controls the operation of solenoids 212 and 213, and has one pole thereof connected 55 to bus bar 206 by a wire 221. A second wire 222 connects the other pole of switch 220 with the lower end of solenoid 213, a third wire 223 connects the upper end of said solenoid with the upper end of solenoid 212, while a fourth wire 224 60 connects the lower end of solenoid 212 with bus bar 204. The solenoids are thus connected for simultaneous operation and when switch 220 is closed valve elements 169' and 173' will be urged upon their respective seats, thereby causing the 65 fluid from pump P to by-pass through pipe 164', as previously described. When this occurs platen 140' will be held against further movement. Upon deenergization of the solenoids springs 216 and 218 will restore the parts to normal position, and the operation of platen 140' will be resumed.

While the embodiments herein described are admirably adapted to fulfill the objects primarily stated, it is to be understood that it is not in- 75

tended to limit the invention thereto since it may be embodied in other forms, all coming within the scope of the claims which follow.

What is claimed is:

- 5 1. In a fluid system, the combination with a reversible discharge pump, having a pair of pipes leading therefrom, of means for controlling the flow of fluid through said pipes, comprising a stroke control element operatively connected to said pump, a spring loaded toggle operative on said element, pressure responsive means operative on said toggle to condition the same for operation in either direction under predetermined conditions, latch means adapted to retain said toggle and stroke control element in neutral position, means for releasing said latch, additional means for urging said toggle in one direction upon the release of said latch, means for rendering said latch means ineffective when said toggle swings past neutral position in the opposite direction, and common actuating means for said releasing means and additional means.
- 10 2. In a fluid system, the combination with a reversible discharge pump, of a stroke adjusting element for said pump, means responsive to the pressure changes in said system for controlling the operation of said pump, said means including a spring loaded toggle operatively associated with said stroke controlling element, latch means for retaining said toggle in neutral position, means mounted on said latch for rendering the latter ineffective when the toggle moves in one direction, said last mentioned means being ineffective when the toggle swings in the reverse direction whereby the latter is held against movement when it assumes a neutral position, means for releasing said latch, and means for urging said toggle in the said reverse direction upon release of said latch.
- 15 3. In a fluid system, the combination with a reversible discharge pump, of a stroke adjusting element for said pump, load and fire mechanism operatively connected to said element, said load and fire mechanism when moved in one direction from a neutral position conditioning said pump for discharge in one direction, and when moved in the reverse direction from neutral said load and fire mechanism conditions said pump for discharge in the reverse direction, latch means comprising a pivotal lever having a notch provided therein for receiving a pin on said load and fire mechanism, a pivotal plate mounted adjacent said notch and adapted to be engaged by said pin, when said load and fire mechanism moves in the reverse direction from which it was urged by said actuating means, to close said notch and thereby permit said load and fire mechanism to complete its movement in said reverse direction to effect a reversal in the discharge of the pump, said plate moving to inoperative position when released by said pin, means for moving said load and fire mechanism in said one direction toward neutral position, and means for urging said lever into engagement with said pin.
- 20 4. In a fluid system, the combination with a reversible discharge pump, of stroke control means for said pump, load and fire mechanism operatively connected to said means and movable to different positions of adjustment to control the flow of fluid in said system, latch means for retaining said load and fire mechanism in neutral position, means for releasing said latch, means for urging said load and fire mechanism in one direction upon release of said latch, and means for rendering said latch means ineffective when said load and fire mechanism moves in the reverse direction, and rendering said latch means effective when said load and fire mechanism moves in said one direction whereby said load and fire mechanism will be held against movement when reaching its neutral position of adjustment.
- 25 5. In a fluid system, the combination with a reversible discharge pump, of a stroke adjust-
- 30 ing element for said pump, load and fire mechanism operatively connected to said element, said load and fire mechanism when moved in one direction from a neutral position conditioning said pump for discharge in one direction, and when moved in the reverse direction from neutral said load and fire mechanism conditions said pump for discharge in the reverse direction, latch means cooperative with said load and fire mechanism for retaining the latter in neutral position, means for releasing said latch, means for urging said load and fire mechanism in one direction upon release of said latch, and means provided on said latch means and engageable by said load and fire mechanism to render said latch means ineffective when said load and fire mechanism moves in the reverse direction.
- 35 6. In a fluid system, the combination with a reversible discharge pump, of a stroke adjusting element for said pump, load and fire mechanism operatively connected to said element, said load and fire mechanism when moved in one direction from a neutral position conditioning said pump for discharge in one direction, and when moved in the reverse direction from neutral said load and fire mechanism conditions said pump for discharge in the reverse direction, latch means cooperative with said load and fire mechanism to retain the latter in neutral position, means for releasing said latch, actuating means for urging said load and fire mechanism in one direction upon release of said latch, said latch means comprising a pivotal lever having a notch provided therein for receiving a pin on said load and fire mechanism, a pivotal plate mounted adjacent said notch and adapted to be engaged by said pin, when said load and fire mechanism moves in the reverse direction from which it was urged by said actuating means, to close said notch and thereby permit said load and fire mechanism to complete its movement in said reverse direction to effect a reversal in the discharge of the pump, said plate moving to inoperative position when released by said pin, means for moving said load and fire mechanism in said one direction toward neutral position, and means for urging said lever into engagement with said pin.
- 40 7. In a device of the class described, the combination with a reversible discharge pump, of a control mechanism for said pump including a stroke adjusting element for said pump, a load and fire mechanism operatively connected to said element, latch means normally retaining said load and fire mechanism in neutral position, means for releasing said latch means and causing movement of said load and fire mechanism in one direction to place the pump on stroke, automatic means for actuating said load and fire mechanism in the reverse direction, means for rendering said latch means ineffective when said load and fire mechanism moves past neutral position in said reverse direction to effect a reversal in the discharge of said pump, a second automatic means for actuating said load and fire mechanism to neutral position, and means for urging said latch means into engagement with said load and fire means to retain the latter in neutral position.
- 45 8. In a device of the class described, the combination with a reversible discharge pump, of a control mechanism for said pump including a stroke adjusting element for said pump, a load and fire mechanism operatively connected to said element, latch means normally retaining said load and fire mechanism in neutral position, means for releasing said latch means and causing move-

- ment of said load and fire mechanism in one direction to place the pump on stroke, automatic means for actuating said load and fire mechanism in the reverse direction, means for rendering said latch means ineffective when said load and fire mechanism moves past neutral position in said reverse direction to effect a reversal in the discharge of said pump, a second automatic means for actuating said load and fire mechanism to neutral position, means for urging said latch means into engagement with said load and fire means to retain the latter in neutral position, and means for varying the time between successive operations of said load and fire mechanism.
15. 9. In a fluid system, the combination with a reversible discharge pump, of a stroke adjusting element for said pump, means for actuating said element in one direction to condition said pump for discharge in one direction, means for actuating said last mentioned means in the reverse direction to condition said pump for discharge in the reverse direction, and means compelling a predetermined cycle of operation of said stroke adjusting element, said last mentioned means comprising a latch adapted to retain said element in neutral position, means for releasing said latch, means for urging said actuating means in one direction upon release of said latch, means provided on said latch for rendering the latter ineffective upon operation of said last mentioned means in the reverse direction, said last mentioned means being so constructed that when said actuating means returns to neutral position said latch becomes effective to retain said actuating means and element in said position.
10. 10. In a fluid system, the combination with a reversible discharge pump, of a stroke adjusting element for said pump, load and fire mechanism operatively connected to said stroke adjusting element, means operated by the pressure developed by said pump for positioning said
- load and fire mechanism to effect reverse operations of said stroke adjusting element, and means compelling a predetermined cycle of operation of said stroke adjusting element, said last mentioned means comprising a latch adapted to retain said element in neutral position, means for releasing said latch, means for actuating said load and fire mechanism in one direction upon release of said latch, means provided on said latch for rendering the latter ineffective upon operation of said load and fire mechanism in the reverse direction, said last mentioned means being so constructed that when said load and fire mechanism returns to neutral position said latch becomes effective to retain said load and fire mechanism and element in said position.
15. 11. In a fluid system, the combination with a reversible discharge pump, of a stroke adjusting element for said pump, load and fire mechanism operatively connected to said stroke adjusting element, means operated by the pressure developed by said pump for positioning said load and fire mechanism to effect reverse operations of said stroke adjusting element, means compelling a predetermined cycle of operation of said stroke adjusting element, said last mentioned means comprising a latch adapted to retain said element in neutral position, means for releasing said latch, means for actuating said load and fire mechanism in one direction upon release of said latch, means provided on said latch for rendering the latter ineffective upon operation of said load and fire mechanism in the reverse direction, said last mentioned means being so constructed that when said load and fire mechanism returns to neutral position said latch becomes effective to retain said load and fire mechanism and element in said position.
20. 12. In a fluid system, the combination with a reversible discharge pump, of a stroke adjusting element for said pump, load and fire mechanism operatively connected to said stroke adjusting element, means operated by the pressure developed by said pump for positioning said load and fire mechanism to effect reverse operations of said stroke adjusting element, means compelling a predetermined cycle of operation of said stroke adjusting element, said last mentioned means comprising a latch adapted to retain said element in neutral position, means for releasing said latch, means for actuating said load and fire mechanism in one direction upon release of said latch, means provided on said latch for rendering the latter ineffective upon operation of said load and fire mechanism in the reverse direction, said last mentioned means being so constructed that when said load and fire mechanism returns to neutral position said latch becomes effective to retain said load and fire mechanism and element in said position.
25. 13. In a fluid system, the combination with a reversible discharge pump, of a stroke adjusting element for said pump, load and fire mechanism operatively connected to said stroke adjusting element, means operated by the pressure developed by said pump for positioning said load and fire mechanism to effect reverse operations of said stroke adjusting element, means compelling a predetermined cycle of operation of said stroke adjusting element, said last mentioned means comprising a latch adapted to retain said element in neutral position, means for releasing said latch, means for actuating said load and fire mechanism in one direction upon release of said latch, means provided on said latch for rendering the latter ineffective upon operation of said load and fire mechanism in the reverse direction, said last mentioned means being so constructed that when said load and fire mechanism returns to neutral position said latch becomes effective to retain said load and fire mechanism and element in said position.
30. 14. In a fluid system, the combination with a reversible discharge pump, of a stroke adjusting element for said pump, load and fire mechanism operatively connected to said stroke adjusting element, means operated by the pressure developed by said pump for positioning said load and fire mechanism to effect reverse operations of said stroke adjusting element, means compelling a predetermined cycle of operation of said stroke adjusting element, said last mentioned means comprising a latch adapted to retain said element in neutral position, means for releasing said latch, means for actuating said load and fire mechanism in one direction upon release of said latch, means provided on said latch for rendering the latter ineffective upon operation of said load and fire mechanism in the reverse direction, said last mentioned means being so constructed that when said load and fire mechanism returns to neutral position said latch becomes effective to retain said load and fire mechanism and element in said position.
35. 15. In a fluid system, the combination with a reversible discharge pump, of a stroke adjusting element for said pump, load and fire mechanism operatively connected to said stroke adjusting element, means operated by the pressure developed by said pump for positioning said load and fire mechanism to effect reverse operations of said stroke adjusting element, means compelling a predetermined cycle of operation of said stroke adjusting element, said last mentioned means comprising a latch adapted to retain said element in neutral position, means for releasing said latch, means for actuating said load and fire mechanism in one direction upon release of said latch, means provided on said latch for rendering the latter ineffective upon operation of said load and fire mechanism in the reverse direction, said last mentioned means being so constructed that when said load and fire mechanism returns to neutral position said latch becomes effective to retain said load and fire mechanism and element in said position, and means for holding said latch releasing means in latch releasing position whereby continued reversals of said pump may be effected.

CARL F. SIBBE.
